UNITED STATES PATENT OFFICE.

CHARLES J. HEISER, OF LOS ANGELES, CALIFORNIA.

THERMOSTATIC VALVE.

Application filed January 29, 1921. Serial No. 440,921.

To all whom it may concern:

Be it known that I, CHARLES J. HEISER, a citizen of the United States, residing at Los Angeles, county of Los Angeles, and 5 State of California, have invented a new and useful Improvement in Thermostatic Valves, of which the following is a specification.

My invention comprises a thermostatic 10 valve which is adapted to be used in water heaters, automobiles or other devices in which there is a liquid circulating system which will hereinafter be explained.

Referring to the drawing which is for illustrative purposes only,

Fig. 1 is a side elevation of water heater equipped with my invention.

Fig. 2 is a side elevation of a portion of an automobile equipped with my invention.

20 Fig. 3 is an enlarged section through my invention, and,

Fig. 4 is a section on a plane represented by the line 4—4 of Fig. 3.

My invention consists of a member 11 25 having a rectangular passage 12 formed therein. The member 11 is threaded at 13 and 14 to receive standard pipe. Secured by means of rivets 15 inside the passage 12 is a thermostatic element 16 formed of two 30 metals having different co-efficients of heat expansion. The element 16 is nearly as wide as the passage 12 and the end thereof extends up against an abutment 17 formed in the wall of the chamber so that in its 35 normal cold position, as shown in Fig. 3, the passage 12 is blocked by the strip 16. For the purpose indicated, the strip 16 need not fit tightly in the passage 12, there being a reasonable clearance allowed therearound.

40 When used in the hot water system, my invention is arranged as indicated in Fig. 1 in which 20 is a storage tank which is supplied with cold water under pressure through a pipe 21 and from which hot 45 water may be taken through a pipe 22. A heater of conventional form 23 takes cold water from the bottom of the boiler 20 through a pipe 24 and delivers hot water through a pipe 25 into the bottom of the 50 member 11, the water passing through the member 11 being delivered to a pipe 26 which is connected to a pipe 22.

The object of using my invention in a hot water heater is as follows:

55 If my invention is omitted and the pipes 25 and 26 are connected together, the heater

tends to circulate water which passes upwardly through the pipe 26 and through the pipe 22 into the top of the boiler 20, water being withdrawn through the pipe 24 to the bottom of the heater 23. Such a circulation is set up even where the water delivered to the pipe 26 is not very warm. There is thus a tendency to heat the water in the boiler 20 to a certain degree which is dependent upon the friction in the pipe 24, the heater 23 and the pipe 26. This can usually be adjusted to give the desired results and if necessary adjustable valves may be used in some portions of the system for this purpose.

Where my invention is used, however, the degree of heat in the top of the boiler 20 is determined by the construction of the element 16 and is entirely independent of other 75 conditions. Suppose that the boiler 20 is full of cold water and the heater 23 is started: The element 16 is in the position shown in Fig. 3 virtually closing the passage 12, the water in the heater 23 is rapidly raised in temperature, the hot water passing upwardly by means of convection currents into the pipe 25. This hot water comes in contact with the strip 16 which expands, moving from the position shown 80 in A to the position shown in B or to an intermediate position shown at B. The strip 16 then extends along one side of the passage 12 and much less obstruction is provided thereby. As soon as the water becomes heated therefor in the heater 23 and not before, the strip 16 bends into the position B, allowing water to pass through the pipe 26 and the pipe 22 into the top of the boiler 20. In the event that the rate of flow 85 is too rapid, the water passing through the passage 12 becomes lowered in temperature and the strip 16 bends back towards the original position, thus shutting off a portion of the water until the desired temperature 90 is reached.

By the use of my invention, it is possible to accurately and positively predetermine the temperature of the water passing into the pipe 26. In other words, if it is desired 105 to deliver this water into the top of the water at 180° F., it is possible to so construct the thermostat strip 16 that at 170° F. it entirely closes the passage 12 and that at 190° F. allows a free circulation. It is thus 110 possible to provide a thermostat which can be accurately made at the factory and which

can be installed by cheap labor with excellent results.

My invention has a further utility when applied to an internal combustion engine shown in Fig. 2, in which 30 is the engine casting which is supplied with cold water through a pipe 31, the hot water being withdrawn through pipe 32. The pipe 31 is taken out at the bottom of the radiator 33, the hot water being delivered to my invention 11 by the pipe 32 passing through a pipe 34 into the top of the radiator. It is very important in the operation of internal combustion engines that the temperature of the cooling water be maintained within definite limits. If the weather is very cold, and the whole system is subjected to low temperatures, the engine has a tendency to remain cold for a long time after it is started due to the rapid cooling of the water in the radiator 33 and to the circulation set up thereby.

It is highly desired in an internal combustion engine to hold the water in the cooling jacket around the cylinder until it reaches a certain minimum temperature after which the circulation can be permitted to establish itself. My invention automatically accomplishes this. In starting the engine, the cooling system is cold and the element 16 is in the position shown in full lines in Fig. 3 in which position it prevents the passage of water from the pipe 32 to the pipe 34. As soon as, however, this water heats up to any desired temperature which temperature is determined by the characteristics of the element 16, the element 16 starts

to bend from the position A towards the position B, and water is allowed to pass from the pipe 32 into the pipe 34. The strip 16 automatically assumes the proper position to maintain this temperature which should be the temperature found by practice to give the best results in the operation of the engine.

It will be noted that my invention is free from valves, stuffing boxes or other devices which might get out of order or leak.

It will be further noted that it is extremely simple to manufacture in its method of operation. It can, of course, be applied to other uses than the two given which are merely for illustration purposes.

I claim as my invention:

1. A thermostatic valve comprising walls 55 forming a flat sided passage; and a thermostatic strip formed of two dissimilar metals and secured at one end, the unsecured end of said strip extending across said passage with its edges parallel with said flat 60 sides and partially closing said passage.

2. A thermostatic valve comprising walls forming a flat sided passage; and a thermostatic strip secured inside said passage, said strip being of suitable material to be distorted by a change in temperature and so placed in said passage that it retards the flow of fluid therethrough by blocking the passage when so distorted.

In testimony whereof, I have hereunto set 70 my hand at Los Angeles, California, this 21st day of January 1921.

CHARLES J. HEISER.
